US00D901617S

(12) **United States Design Patent** (10) **Patent No.:** **US D901,617 S**
Wu (45) **Date of Patent:** **** Nov. 10, 2020**

(54) **FIREWORKS DETONATOR**

- (71) Applicant: **Titan International Technologies, Ltd.**, Hong Kong (CN)
- (72) Inventor: **Kevin Wu**, Hong Kong (CN)
- (73) Assignee: **TITAN INTERNATIONAL TECHNOLOGIES, LTD.**, Hong Kong (CN)
- (**) Term: **15 Years**
- (21) Appl. No.: **29/695,924**
- (22) Filed: **Jun. 24, 2019**

Related U.S. Application Data

- (63) Continuation of application No. 29/615,565, filed on Aug. 30, 2017, now Pat. No. Des. 856,461.
- (51) **LOC (12) Cl.** **22-03**
- (52) **U.S. Cl.**
USPC **D22/112**
- (58) **Field of Classification Search**
USPC D22/112, 199; D14/203.1, 300

(57) **CLAIM**

The ornamental design for a fireworks detonator, as shown and described.

DESCRIPTION

FIG. 1 is a perspective view of a fireworks detonator.
FIG. 2 is a front elevation view of the fireworks detonator of FIG. 1.
FIG. 3 is a rear elevation view of the fireworks detonator of FIG. 1.
FIG. 4 is a left elevation view of the fireworks detonator of FIG. 1.
FIG. 5 is a right elevation view of the fireworks detonator of FIG. 1.
FIG. 6 is a top plan view of the fireworks detonator of FIG. 1.
FIG. 7 is a bottom plan view of the fireworks detonator of FIG. 1; and,
FIG. 8 is a bottom perspective view of the fireworks detonator FIG. 1.
The dashed lines in the figures do not form part of the claimed design.

1 Claim, 6 Drawing Sheets
